US00D992224S

(12) **United States Design Patent** (10) **Patent No.:** **US D992,224 S**
Yang (45) **Date of Patent:** **** Jul. 11, 2023**

(54) **PRESSURE WASHER**

(71) Applicant: **SHENZHEN SAILVAN NETWORK TECHNOLOGY CO., LTD.**, Shenzhen (CN)

(72) Inventor: **Guoqing Yang**, Shenzhen (CN)

(73) Assignee: **SHENZHEN SAILVAN NETWORK TECHNOLOGY CO., LTD.**, Shenzhen (CN)

(**) Term: **15 Years**

(21) Appl. No.: **29/816,106**

(22) Filed: **Nov. 18, 2021**

(30) **Foreign Application Priority Data**

Nov. 15, 2021 (EM) 008757736-0001

(51) **LOC (14) Cl.** **15-05**

(52) **U.S. Cl.** **D32/15**
USPC .....

Primary Examiner — Khawaja Anwar
Assistant Examiner — Taylor O Mortorff

(57) **CLAIM**

The ornamental design for a pressure washer, as shown and described.

DESCRIPTION

FIG. 1 is a perspective view of a pressure washer showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the pressure washer that form no part of the claimed design.

1 Claim, 8 Drawing Sheets
